WALL MOUNTED LIGHTING FIXTURE FOR MIRRORS OR THE LIKE

Guy Vrignaud, Grenoble, France, assignor to Allibert Exploitation, Puteaux, France

Filed Nov. 6, 1974, Ser. No. 521,490

Claims priority, application France May 6, 1974

Term of patent 14 years

Int. Cl. D26—05

U.S. Cl. D48—20 F

FIG. 1

FIG. 3

FIG. 2

FIG. 4

FIG. 5

FIG. 6

FIG. 1 is a perspective view of a wall mounted lighting fixture for mirrors or the like showing my invention;

FIG. 2 is an end elevational view thereof, the other end elevational view being identical except for the absence of the pushbutton and pushbutton bracket;

FIG. 3 is a front elevational view thereof;

FIG. 4 is a rear elevational view thereof;

FIG. 5 is a top plan thereof; and

FIG. 6 is a bottom plan view thereof.

I claim:

The ornamental design for a wall mounted lighting fixture for mirrors or the like, as shown and described.
